TO SAID PHILPOTT

COLLAPSIBLE HORSE

Application filed May 24, 1928. Serial No. 280,151.

This invention relates to a collapsible horse.

The horse of the invention is a workman's horse made with the legs so hinged and associated that the legs may be collapsed against the underside of the body of the horse whereby the same may be readily carried from place to place and conveniently stored. The legs are so arranged as to be rigidly secured 10 against collapse when in open position.

An object of the invention is to provide a collapsible horse which may be readily collapsed or opened for convenient use.

Another object is to provide a collapsible horse which is economical to manufacture, which is strong, sturdy and efficient in use.

A further object is to provide a collapsible horse with means for preventing collapse while in use.

According to the invention the two pairs of legs are each hinged to a plate which plate is in turn hinged to the body of the horse. Means are provided for locking the legs in extended position.

Other and further objects will be apparent from the following description, drawing and appended claims.

One form of the invention is shown in the accompanying drawing and the views there- 10 of are as follows:

Figure 1 is a side elevation showing in dotted lines the position of the legs when collapsed.

Figure 2 is an end elevation of the horse 35 of Figure 1.

Figure 3 is a bottom plan view of the horse with the legs in collapsed position.

Figure 4 is an enlarged section on line IV-IV of Figure 1.

Figure 5 is a section on line V-V of Figure 4.

Figure 6 is a section on line VI-VI of Figure 4.

Figure 7 is an enlarged section on line VII-VII of Figure 2.

The horse comprises a body 1 which may be made of wood and which is substantially rectangular in cross-section.

Adjacent each end of the body 1 and secured to the under part thereof as by screws

2, is a hinge plate 3 having a pintle 4 which is transverse to the body 1 of the horse. A plate 5 is hinged to the plate 3 by the pintle 4 and the plate 5 is shown as somewhat larger than the plate 3. The plates 3 and 5 and the 55 pintle 4 constitute a hinge.

The side margins of the plate 5 have portions 8 and 9 thereof formed into cylindrical shape and hollow from end to end constituting portions of lateral hinges.

Plates 7 have cylindrical portions 6 which are secured by means of pintles 10 to each of the members 8 and 9 of the plate 5. This construction constitutes a double hinge comprising a plate 5 and the two side members 7. 60

The legs 11 and 12 of each pair are fastened to the hinge members 7 by means of straps 13 formed into substantially U-shape in end elevation having projecting ears 14 at the ends. The straps 13 are fastened to the legs and the members 7 of the hinges by rivets 15 or like attaching members.

The ears 14 are substantially triangular in end elevation and are provided with apertures through which the pintles 10 pass and 75 over which the pintles are headed to securely fasten the legs to the hinge.

The plates 7 of the hinge extend upwardly at obtuse angles, forming walls 16, which, when the legs are spread to support the horse 80 as shown in Figures 1, 2, 3 and 6, lie between the chamfered faces 17 of the upper end of the legs. The inner surfaces of the walls 16 are provided with prongs or detents 18 along the upper edges of the wall 16 and intermediate projections 19 for entering the body 1 to prevent collapse of the spread legs lengthwise of the body member while in service. The prongs 18 and 19 are embedded in the wood of the member 1 and these lock the plate 85 5 against the underside of the body 1 so that the hinge comprising the parts 3, 5 and 4 will not pivot about the pintle 4.

The legs 11 and 12 are connected by links 20 and 21, the outer end of each link being pivoted at 22 and 23 to the legs 12 and 11 respectively and pivoted to each other at 24. The link 20 is longer than the link 21 and has an overlapping portion 25 carrying a tongue or projection 26 at its end, which, when the legs 100

are spread as in Figure 2, enters a notch 27 in the other link 21, thus securing the links 20 and 21 in extended position for maintaining the legs 11 and 12 in spread position.

5 The horse shown in Figures 1 and 2 is as it appears when in use. In this position the legs 11 and 12 are spread, the links 20 and 21 moved so that the axes of the same lie in the same straight line and the detents or prongs 18 and 19 of the side walls 7 of the lateral hinges are embedded in the side of the body 1, thus preventing collapse of the structure.

10 The arrangement of parts just described provides a rigid serviceable structure and one 15 which is not collapsed by accident.

Figure 3 shows the underside of the horse with the legs collapsed.

20 When the device is to be collapsed, the pivot 24 of the links 20 and 21 is moved upwardly, drawing the outer ends of the legs 11 and 12 together, thus freeing the detents 18 and 19 from engagement with the sides of the body 1. The legs may then be moved about the 25 pintles 4 into the position shown in Figure 3 with the side edges of the legs against the underside of the body 1.

25 The horse being collapsed, as just described, may be carried readily from place to place or stored if desired. When the same is to be used 30 at another time, the legs are swung about the pintles 4 until the plate 5 contacts the under surface of the body 1, whereupon the legs are spread, moving the links 20 and 21 from the 35 position shown in Figure 3 to the fully extended position shown in Figure 2 whereupon the structure is securely locked in service position.

40 It is within the scope of our invention to make the horse of material other than wood, 45 in which event the prongs 18 and 19 would enter properly arranged and shaped apertures at the sides of the body 1.

45 While we have described more or less precisely the details of construction of our invention, yet we do not wish to be understood as limiting ourselves thereto, as we are aware that changes may be made in the arrangement and proportion of parts and that equivalents may be substituted, all without departing 50 from the spirit and scope of our invention.

We claim as our invention:

1. A collapsible horse including a body, a pair of legs near each end of said body, each pair of legs being connected to said body for 55 hinging action transversely and longitudinally of said body, hinges connecting the legs to the body, each hinge including a plate fastened to the underside of the body with a pintle transversely of said body, and a second hinge plate connected to said pintle, said second hinge plate having wings hinged to the side edges thereof by pintles longitudinally of said body, the legs of a pair being connected to the wings of a hinge, and said wings having portions thereof extending above the

50 pintles thereof, said portions having prongs thereon for engagement with said body when said legs are spread, the engagement of said prongs with said body preventing hinging action of the legs about the transverse pintles when the legs are spread.

55 2. A collapsible horse including a wooden body, a pair of legs near each end of said body, each pair of legs being connected to said body for hinging action transversely and longitudinally of the body, hinges connecting the legs to the body, each hinge comprising a plate fastened to the underside of the body with the pintle transversely thereof and a second plate connected to said pintle, said second hinge plate having wings hinged to the side edges thereof by pintles longitudinally of the body, the legs of a pair being connected to said wings, said wings having portions for attachment to the legs and other 60 portions provided with projections for engaging said wooden body when the legs are spread about the longitudinal pintles, said projections being moved into engagement with said body by movement of said legs to spread position, the engagement of said projections with said body preventing hinging action of the legs about the transverse pintles when the legs are spread.

65 3. A collapsible horse comprising a body, a pair of spreadable legs arranged near each end of said body, hinges connecting each pair of legs to said body, said hinges including a plurality of hinge plates, certain of said plates being connected to said body with the pintles 70 thereof arranged transversely of the body and others of said plates being secured to said legs and longitudinally hinged to certain of the plates connected to the transverse pintles, said leg plates having projections 75 thereon to enter said body when said legs are spread to prevent hinging action of the legs about said transverse pintles.

80 4. A collapsible horse comprising a body, plates adjacent each end of said body and hinged thereto with the pintles extending transversely of the body, a pair of leg carrying members hinged to each plate with the pintle axes thereof perpendicular to the first named pintles respectively, a leg in every one 85 of said members, spreaders connecting the two legs of each pair, said leg carrying members having plates extending adjacent said body when the pair of legs are spread, and a prong on every one of said last named plates 90 for entering said body when each pair of legs is spread to prevent collapse of the legs about said transverse pintles respectively.

95 5. A collapsible horse comprising a body, a pair of spreadable legs arranged near each end thereof, said legs being connected to said body in a manner to allow hinging action lengthwise and transversely of the body, the connection between said legs and said body including plates hinged near each end of the 100

body with the pintles thereof arranged transversely of the body, side members hinged to said plates by pintles perpendicular to said first named pintles, said legs being secured to said side members, said legs having spreaders therebetween to lock the legs in open spread position, the side members having prongs thereon for entering said body when said legs are spread to prevent collapsing action of said legs about the transverse pintles of said plates while said horse is in use.

In testimony whereof we have hereunto subscribed our names at Chicago, Cook County, Illinois.
